UNITED STATES PATENT OFFICE

2,674,688

COMBINATION INCANDESCENT AND FLUORESCENT WALL TROFFER LIGHTING FIXTURE

Abraham H. Feder, New York, N. Y.

Application October 3, 1949, Serial No. 119,378

5 Claims. (Cl. 240—51.11)

1

The present invention relates to a lighting arrangement and it particularly relates to illuminated lighting arrangements which may be positioned adjacent or against walls or other parts of rooms, buildings and so forth.

It is among the objects of the present invention to provide novel lighting fixtures in which fluorescent as well as incandescent lighting may be widely utilized to illuminate walls and give a desired high degree of effective illumination to show-rooms, hotel lobbies, store windows, as well as in homes and offices.

Another object is to provide a simple, inexpensive, decorative lighting fixture which may be widely utilized in show-rooms, offices, drafting rooms and other places where wall lighting is most desirably employed.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Fig. 1 is a front plan view of one portion of one type of lighting fixture, according to the present invention.

Fig. 2 is a transverse vertical sectional view taken upon the line 2—2 of Fig. 1.

Fig. 3 is a transverse vertical sectional view taken upon the line 3—3 of Fig. 2.

Fig. 4 is a front elevational view of an alternative form of lighting fixture which may be mounted upon a wall or otherwise positioned in a room or interior to be illuminated and which is designed to carry fluorescent lighting.

Fig. 5 is a transverse vertical sectional view upon the line 5—5 of Fig. 4.

Fig. 6 is a front plan view of a fluorescent lighting arrangement particularly designed to be suspended along a wall or over door recesses.

2

Fig. 7 is a transverse vertical sectional view upon the line 7—7 of Fig. 6.

Fig. 8 is a transverse sectional view upon the line 8—8 of Fig. 7.

Fig. 9 is a front plan view of still another embodiment of a lighting arrangement.

Fig. 10 is a transverse vertical sectional view upon the line 10—10 of Fig. 9.

Fig. 11 is a transverse vertical sectional view of still another embodiment of wall lighting fixture.

Referring to Figs. 1 to 3, the light fixture A is designed to be placed upon the wall B and it carries a plurality of reflector lamps C as well as fluorescent lamps D and E.

As indicated, the casing or fixture A has a front wall 10 which may be opaque or translucent and a rearwardly inclined wall 11, the lower end of which is upturned as indicated at 12 on Fig. 3.

The top of the wall 10 is turned over, as indicated at 13, and engages a hinge pin 14. The hinge pin 14 is also engaged by the upper edge of the plate 15. The plate 15 is held by the rivets 16 upon the upper end 17 of the bracket 18. The bracket 18 has a forwardly offset vertical portion 19 carrying screws 20 which are mounted upon an iron strap reinforcement 21. The reinforcement 21 is applied to the wall 22 of a box 23 having the overlapping top walls 24 and the overlapping bottom walls 25 held together by the screws 26 and 27. The rear wall 28 has openings 29 enabling attachment to the wall B.

The bottom of the bracket 18 has a rearwardly offset vertical portion 30 with a horizontal forwardly extending flange 31. The flange 31 carries the screw 32 which passes through the flat portion 33 of the bracket 34. The bracket 34 is spot welded at 35 to the lower portion 36 of the wall 11.

The wall 22 at intervals carries the sockets 37 for the fluorescent tubes D and E.

To carry the reflector lamps C, the angle sockets 38 are provided, having spun light shields 39 slotted at 51 to enable friction grip. Below the relatively flat bulbs 40 of the reflector lamps C are positioned grille louvers 41 which consist of a series of longitudinal plates 42 filling the opening inside of the ring 43.

The ring 43 has a vertical flange 44 and a horizontal flange 45. The horizontal flange 45 rests on or is spot welded to the edge 46 of the cut-out 47 in the base plate 11. The vertical flange 44 is encircled by the nipple 52 of the shield 48, which has an upstanding portion 49 forming a cup-like enclosure around the bottom 40 of the 55 reflector lamp C.

The angle socket 38 is mounted by the transverse extension 60 (see Fig. 1). The extension 61 is held on the arm 61 by a nut 62. The arm 61 constitutes a bent extension of the element 63 of the bracket 64. The bracket 64 is held in place by the screws 65.

By the arrangement shown in Figs. 2 and 3, the fluorescent tubes D and E together with the reflector lamps C give a desired illumination upon the wall in both upward and downward directions. The tubes D and E cast light upwardly while the reflectors 49 and bulbs C cast light upwardly and downwardly.

The arrangement is quite compact and decorative when viewed from below and is readily accessible for repair and replacement in respect to the tubes D and E as well as the bulbs C.

The arrangement is readily made of sheet metal and is readily mounted in position, particularly as shown in Figs. 1, 2 and 3.

By the arrangement shown in Figs. 4 and 5, there is shown a rear supporting structure F, tubes G, sockets H and a shield structure J.

The arrangement shown in Figs. 4 and 5 is particularly adaptable to a wall troffer arrangement in which the front member consists of an inwardly curved shield 75 with an inturned upper edge 76 and an inturned lower edge 77. The lower edge is spot-welded to the flange 78 of the continuous angle iron 79 which has a vertically upwardly directed flange 80.

The lower, inturned portion 77 also has an upturned element 81 carrying the edge 82 of the polished aluminum reflector 83. This reflector has an out-turned flange 84 which rests upon the inturned flange 85 of the angle member 86. The angle member 86 is spot-welded, as indicated at 87, to the rear of the curved front section 75. The screw or bolt element 87 and the cooperating nut element 88 serve to hold the flanges 84 and 85 together.

At the rear of the fixture is the back wall supporting element F having the wall-contact flanges 95 which carry the wall-locking tubes 96 and 97 which are pivotally connected to said tubes at 98. The tubes 96 are held to said plates 95 by the screws 99.

The plates 95 are provided with outwardly extending flanges 100 and 101. The flange 100 carries the horizontal section 102 of the angle member 103 by means of the screws 104.

The screws 104 extend through the horizontal flange 105 of the U-member 103. The members 103 and 106 have the downwardly extending plate members 107 and 108 which have openings to receive the projecting socket base 110 from the socket 109. The socket 109 carries the fluorescent tubes G.

The plate 107 is turned inwardly, as indicated at 111 and downwardly at 112, where the nut 113 and the screw 114 attach it to the wall plate 95.

The bottom plate 101 is turned upwardly, as indicated at 115, to support the inturned bottom edge 116 of the front plate 117. The front plate 117 carries the angle support member 118 which is welded at the vertical flange 119 to the plate 117 and has a horizontal flange 120. The flange 120 and the flange 121 support the horizontal glass pane 121 through which the light from the tube G passes downwardly in the direction indicated at 122. The bracket 123 has an upstanding forward flange 124 spot-welded at 125 to the front plate 117. The bracket 123 has a horizontal member 126 with an upstanding flange 127 spot-

welded at 128 to the plate 117 and supporting the flange plate 129 from the box F.

The sockets H are held in position by the screws 129a on the plates 107 and 108. The ends of the fixture may be closed by the curved end plate 129 or by the square end plate 130. The connecting sections of the plate 129 are preferably provided with lightproof overlaps, indicated at 131 in Fig. 4. The end, upturned flanges 132 also serve to support the ends of the glass 121.

As shown in Figs. 4 and 5, light is directed upwardly, as indicated by the arrow 132, as well as downwardly, as indicated by the arrow 122, to give a most effective wall illumination.

In the embodiment of Figs. 6, 7 and 8 is shown a wall troffer which is particularly designed to be positioned over the entrance of doors or upon walls to give indication of room numbers, directions, and other information. As shown in Figs. 6, 7 and 8, there is provided rear structure K and forward structure L within which are positioned the sockets M, the fluorescent tubes N and bulbs R.

The structure K has a top flange 140 and a vertical rear flange 141. Held in the corner 142 is the ballast 143. The flanges 144 of the ballast 143 are held by element 146 and the screw 147.

The vertical flange or plate 141 carries the back plate 146 which has an inwardly and rearwardly turned bottom flange 148. On the back plate 146 is mounted the vertical plate 150 and the inturned flange 158.

The oblique, removable ballast access plate 151 terminates at 152 and is bolted at 154 to the plate 155. The plate 155 is held in position by the nut 156. Plate 155 is turned downwardly at 157 and clamped to the plates 141, 146 and 150 by the screws 158.

The bottom edge of the plate 141 (see Fig. 8) is turned forwardly at 159 where it contacts the base plate 160 carrying the screw 161. The base plate 160 supports the edge 163 of the glass 164 by the forwardly projecting portion 165. The lugs 166 and 167 together with the collar 168 help support the bolt 160. The bolt 160 extends through and into the plate 155. The flange 169 (see Fig. 8) holds the glass 164 in position.

The upper end of the oblique plate 141 is bolted to the lower end 181 of the plate 182 by the screw 183 and the nut 184. The vertical flange 185 extends downwardly from the horizontal flange 186 which has the screw 187. The horizontal flange has a downwardly inclined portion 188. The screw 187 passes through the forward end 189 of the plate 140 and also through the flange 190 of the angle member 191 and the flange 192 of the angle member 193. The angle member 193 has a strap hanger 194.

The hinge construction 195 carries the skirt member 196 as well as the offset member 197 between which is clamped at the upper end 198 of the front glass section 199.

Between the sections illuminated by the fluorescent tubes N may be positioned the numeral sections P and Q, which are illuminated by the bulbs R. The bulbs R are supported by the porcelain sockets 210 upon the front or removable access ballast plate 151, already previously described.

The numeral sections P and Q may be formed in a removable plate 211 having cut-outs at 212 and extending, as indicated at 213, over the entire inner face of the longitudinal glass angle structure 199 and 164. The tubes N and the bulbs R may be of many intensities and sizes and the

bulbs R may be, for example, of 7½ watt capacity.

The arrangement shown in Figs. 6, 7 and 8 particularly adapted itself to be fitted to recesses above doors and hallways, to room numbers, to wash rooms, directions to fire escapes, directions to elevators, to indicate the position of telephones and for many other purposes where it is desired to give unobstructed and concealed lighting in and about hotels or office buildings, lobbies, offices, rooms and serving pantries. The entire arrangement is most readily installed and permits ready swinging away of the front casing L to permit replacement of the tubes N or the bulbs R or access to the ballast 143.

In the arrangement shown in Figs. 9 and 10 there is shown a rear support S carrying the ballast T, a front cover W, the upper double tubes V and X and the lower egg crate louvers Y.

The arrangement shown in Figs. 9 and 10 is particularly adapted for a double troffer with two fluorescent tubes throwing light upwardly and the inner one also throwing illumination downwardly.

The rear structure S includes a wall plate 225 with the screws 226 and 227 and the opening 228. The wall plate 225 has the inturned upper flange 229 and the inturned lower flange 230 which are respectively connected to the flanges 231 and 232. The screws 233 extend through the flanges 229 and 231. The flange 231 is bent downwardly at 234 to form a vertical section 235 which is spot-welded at 236 to the upper end 237 of the flange 238. The flange 238 is bent upwardly at 239 from the base flange 232. The flange 238 has a forwardly extending lip 240 which supports the rear end of the plates 241 and 242 of the egg crate louvers Y. The forward end of the egg crate louvers Y is supported on the shoulder 243 of the upturned aluminum reflector 244, which has a lower inturned flange 245 spot-welded at 236 to the front member 238, forming part of the structure W.

The inturned shoulder 243 of the aluminum reflector 244 has an upturned lip 249 which rests on the horizontal flange 250 of the upturned plate 251. The plate 251 is spot-welded at 252 to the curved front member 248. The cross bracket 265 is turned downwardly at 266 to form the member 267 spot-welded at 268 to the front plate 248.

The bracket 265 is also turned downwardly at 270 and spot-welded at 269 to the plate 235. Above the brackets 265 are the receptacles 271 and 272 for receiving the bases 273 and 274 of the socket 275 and 276. Sockets 275 and 276 have flanges which are held in position by the screws 277 and 278. The ballast T has a back 280 with a front 281 held in position by the screws 282.

As indicated in Fig. 9, the end of the casing is provided with the curved end plate 290 and with the square, closed end 291. The sockets X and V may be connected back to back by the brackets 292, as shown in Fig. 9. The ends of the recess 293 where the light is directed downwardly, as indicated by the arrow 294, may be closed off as indicated by the curved end plates 295.

There is shown in Figs. 9 and 10 a novel wall troffer which gives double illumination upwardly, as indicated by the arrows 296 and 297, and single illumination, as indicated at 294 downwardly. Here too the ballast and the tubes Z are most readily accessible for repair and replacement and the entire arrangement may be most

readily installed with a minimum of difficulty in office buildings, homes and hotels as well as shops to give maximum illumination upwardly and downwardly.

- 5 In Fig. 11 is shown another embodiment of wall troffer having a wall box 400 with rearwardly directed flanges 401 and 402 mounted on the wall structure 403 having the base 404 and base strip 405.
- 10 The twin tubes 406 and 407 are mounted in sockets 408 and 409 having base structures 410 and 411 mounted by screws 412 and 413 in mounting plate 414.

The glass front 415 has its lower rearward edge mounted at 416 on strip 405 and it extends upwardly and forwardly at 417 to point 418. At its ends it is supported on the end plate 419. The ballast 420 with base 421 is also supported by screws 423 on end plate 419.

15 The illumination is directed forwardly and downwardly as indicated by arrows 424 and 425.

20 While there has been herein described a preferred form of the invention, it should be understood that the same may be altered in details and 25 in relative arrangement of parts within the scope of the appended claims.

Having now particularly described and ascertained the nature of the invention and in what manner the same is to be performed, what 30 is claimed is:

1. A wall troffer lighting arrangement comprising a wall support member, a plurality of socket supports for elongated fluorescent lighting elements and an elongated translucent partial enclosure for said elements, said socket supports being mounted upon said wall support member and said wall support member having a forwardly extending bracket provided with a hinge mount at the upper outer end of the bracket and the upper end of said elongated translucent partial enclosure having a pivotal connection to said hinge mount and said elongated translucent partial enclosure having only a front wall and a bottom wall and means to connect the lower inside end of said bottom wall to said wall support member.

2. A wall troffer lighting arrangement comprising a wall support member, a plurality of socket supports for elongated fluorescent lighting elements and an elongated translucent partial enclosure for said elements, said enclosure being mounted upon a hinge to enable it to be swung away from said support for replacement of said elements, said socket supports being mounted upon said wall support member and said wall support member having a forwardly extending bracket provided with a hinge mount at the upper outer end of the bracket and the upper end of said elongated translucent partial enclosure having a pivotal connection to said hinge mount and said elongated translucent partial enclosure having only a front wall and a bottom wall and means to connect the lower inside end of said bottom wall to said wall support member.

3. A wall troffer lighting arrangement comprising a wall support member, a plurality of socket supports for elongated fluorescent lighting elements and an elongated translucent partial enclosure for said elements, and reflector means for directing the illumination upwardly and downwardly, said socket supports being mounted upon said wall support member and said wall support member having a forwardly extending bracket provided with a hinge mount at the up-

per outer end of the bracket and the upper end of said elongated translucent partial enclosure having a pivotal connection to said hinge mount and said elongated translucent partial enclosure having only a front wall and a bottom wall and means to connect the lower inside end of said bottom wall to said wall support member.

4. A combination incandescent and fluorescent wall troffer lighting fixture having a plurality of groups of parallel vertically superimposed fluorescent tubes with an intervening incandescent bulb comprising a wall mounting structure, sockets for said tubes positioned on said structure, brackets mounted on said structure having outwardly and upwardly extending upper and lower legs, a partial elongated translucent enclosure having a front vertical wall and a rearwardly and downwardly extending bottom wall, a hinge connection between the upper edge of the front vertical enclosure wall and the ends of the upper bracket legs and a screw connection between the

lower bracket legs and the lower edge of the bottom enclosure wall.

5. The fixture of claim 4, the upper legs of said brackets extending outwardly between said tubes.
